UNITED STATES PATENT OFFICE

110,841

DESIGN FOR A MANUAL CONTROL DISPENSING NOZZLE

John H. Tobler, Waterbury, Conn., assignor to Scovill Manufacturing Company, Waterbury, Conn., a corporation of Connecticut

Application March 5, 1938, Serial No. 75,624

Term of patent 14 years

To all whom it may concern:

Be it known that I, John H. Tobler, a citizen of Switzerland, residing at Waterbury, county of New Haven, State of Connecticut, U. S. A., have invented a new, original, and ornamental Design for a Manual Control Dispensing Nozzle, of which the following is a specification, reference being had to the accompanying drawing, forming part thereof, in which,—

Fig. 1 is a side elevational view of the manual control dispensing nozzle showing my new design.

Fig. 2 is a similar view showing the reverse side.

Fig. 3 is an end view as the nozzle appears from the left end of Fig. 2, and

Fig. 4 is an end view as the nozzle appears from the right end of Fig. 2.

I claim:

The ornamental design for a manual control dispensing nozzle, substantially as shown.

JOHN H. TOBLER.
